(57) **CLAIM**

We claim the ornamental design for a headset for measuring brain waves, as shown and described.

DESCRIPTION

FIG. 1 is the front perspective view of a headset for measuring brain waves showing our new design; FIG. 2 is the front view thereof; FIG. 3 is the rear view thereof; FIG. 4 is the left-side view thereof; FIG. 5 is the right-side view thereof; FIG. 6 is the top plan view thereof; FIG. 7 is the bottom plan view thereof; and, FIG. 8 is the partially enlarged view of FIG. 1.

The broken lines in the drawing show unclaimed environment only and form no part of the claimed design. The dot-dash broken lines encircling portions of the claimed design that are illustrated in enlargements form no part of the claimed design.
